UNITED STATES PATENT OFFICE

ARTHUR DORSEY, OF BROOKLYN, NEW YORK

CLOCK

Application filed December 23, 1922. Serial No. 608,600.

This invention relates to certain improvements which are generally applicable to clocks but which are designed primarily for incorporation in a clock which is used for the purpose of delivering power of appreciable extent, either continuously or periodically, as distinguished from a clock which merely serves the purpose of actuating time indicating elements. For convenience in this description but without limitation on the scope or uses of the invention there has been illustrated in the drawings a clock which is so constructed as to not only indicate time but also actuate power take-off elements which engage periodically other elements to be actuated under the power delivered by the clock, for the doing of useful work, as in the tripping of levers to control electric switches. Accordingly, the description will be given with respect to this specific application, in the interest of clearness, but wherever reference appears either in the specification or claims to the power take-off arms or the elements actuated thereby it is to be understood that power may be taken off by other means and may be employed to serve other purposes.

One of the principal objects of the invention is to construct a clock in which the parts are so disposed as to make it unnecessary for the power taken off to be led through the clock train. Heretofore, it has been the practice in constructing clocks having power take-offs, to take the power off a lay shaft which is operatively connected through at least a part of the clock train with the driving power, such as a main spring. The effect of this relation is that when the greatest amount of power is being delivered the greatest amount of friction is set up in the transmission elements so that the frictional losses are greatest at the very time when the demand is greatest. This relatively great frictional loss means that the machine as a whole is inefficient and necessitates the use of a prime mover of greater capacity than would otherwise be necessary. Further, variations in power impressed upon the clock train in a construction of this kind necessarily affects adversely the time indicating accuracy since,

generally speaking, the accuracy of a time piece is dependent upon the constancy of the load and the maintenance of unchanging conditions with respect to all of the parts.

By providing for this condition the prime mover, in order to deliver a given amount of power to the power take-off may be of substantially lesser capacity than heretofore since the efficiency of the construction insures the delivery of a relatively great amount of power in useful form. The result described is accomplished, in general, by dividing the power at its source and leading so much of the power through the clock train as may be necessary for accurate operation of the time piece and the remainder to the power take-off through means which are physically and mechanically independent of the elements of the clock train.

Other objects of the invention have to do with structural features which are of importance in supporting the clock mechanism within the case, strengthening the case, and in mounting the case removably on a support. Other features are concerned with the construction of the power take-off elements and the time indicating members by which adjustments in the time indicating mechanism itself may be made without disturbing the power take-off devices and by which the power take-off devices may be adjusted for sequential operation.

The invention will be described with greater particularity hereinafter with reference to the embodiment thereof pointed out hereinbefore. In the drawings:

Figure 1 is a view in front elevation of the improved clock showing time indicating mechanism, power take-off arms and an element to be actuated.

Figure 2 is a view in vertical section through the parts shown in Figure 1.

The clock case *a* may be formed of one piece drawn to a cup and having at its rear edge an annular flange *a'* to which is secured a back plate *b* which is dished for strength as indicated at *b'* and lapped on the flange *a'* to insure a firm connection therebetween and offer a trussed support for the mechanism which is to be supported thereby. The case thus

formed of two parts is adapted to be supported removably on a panel or in like manner indicated at *c* by means of three screws *d*, *d'*, *d''*, which pass through the flange *a'* and the lapped portion of the back plate *b*. Two of the screws *d*, *d'*, are placed at equal distances on opposite sides of the center line of the case and near enough to the center line to effectively support the weight and resist torsional stresses. The third screw *d''* is placed on the center line of the case at its upper side, passes through a slot *a''* formed in the flange *a'* and the lapped portion of the back plate *b* to facilitate removal of the case especially in closely confined spaces. The removal may be effected by loosening the screw *d''* and then withdrawing the screws *d*, *d'*, whereupon the case may drop away from the screw *d''*. This screw will serve the purpose of locating the case when it is to be mounted.

The supporting frame for the clock mechanism indicated generally at *e* is firmly mounted within the case by means of front and back nuts *f*, *f'*, which may engage rods *e'* of the frame which extend between the front and rear walls of the case and act as trusses as well as supports. By loosening all of the front nuts *f'* and removing the back plate *b* it is evident that the entire clock mechanism may be withdrawn as a unit.

While the invention is not concerned with any of the structural details of the parts of the clock mechanism as such it is concerned with the relation of the constituent elements thereof for the purpose of securing maximum accuracy and efficiency. The barrel *g* has one end of the main spring *h* secured thereto, the other end of the main spring being secured to the arbor *i*. Rotation of the barrel to compress the main spring may be effected in any suitable manner as through a gear *g'* which may be revolved through winding mechanism. The arbor is free to rotate under the influence of the spring. A clock train of any suitable form is connected operatively at the rear side of the main spring *h* to the arbor *i*, several of the wheels of this clock train being indicated at *k*. A governor or escape of suitable form is indicated conventionally at *k'*. Rotation of the arbor under the influence of the main spring is controlled by the escape in the usual manner. The front end of the arbor extends through the case *a* and carries thereon through any suitable securing devices means from which power may be taken off of the arbor either continuously or periodically for the purpose of doing useful work. In the illustrated embodiment two arms *l* are shown as secured operatively to the arbor *i* and extending radially therefrom, these arms being adapted to deliver power as to other elements *m*, *m'* disposed respectively in their paths when revolved with the arbor. It may be assumed, for instance, that the two arms *m*, *m'* actuate switch mechanism. Whether

or not power is taken off of the arbor continuously or, as illustrated, periodically, the improved construction insures delivery of maximum power depending upon the capacity of the source (the main spring) with minimum losses in friction and least disturbances which affect the accuracy of the time indicating mechanism.

In order to secure the power take-off elements and the time indicating devices to the arbor and permit their adjustment with respect to each other and with respect to the arbor, the latter has secured thereto a screw *i'* which has secured to its outer end a frictional lock nut *i''*. On the screw *i'* is disposed loosely a sleeve *o* which is shouldered to bear against the end of the arbor. This sleeve may carry adjacent its mid-section an annular bushing *o'* on which may be mounted a time indicating dial *p* and the power take-off arms *l*. The sleeve *o* is also shouldered as at *o''* to provide a bearing surface against which the elements *l* and *p* may be jammed for locking. A lock nut *q* is threaded on the exterior of the sleeve *o* and bears against one of the elements *l*, *p* to jam the three of them in locking engagement against the shoulder *o''*. From the description given it will be evident that when the nut *i''* is screwed on it will engage the outer end of the sleeve *o* and unite all of the parts so as to rotate with the arbor *i*. When the nut *i''* is backed off the sleeve *o* may revolve freely thereon with the elements *l*, *p*, but these elements will be maintained in fixed relation to each other by means of the jam-nut *q*. However, the relation between the parts *l*, *p*, may be changed by backing off the jam-nut *q* as will be evident. To the case is secured a suitable pointer *r* which co-operates with the time indicating dial *p* in such manner as to indicate the time. Each of the arms *l* may be scored as at *l'* so that they may be conveniently set in such relation to the time indications on the dial as to be adapted to perform their intended functions and deliver power at any predetermined time.

Changes in the details of construction of any of the parts may be made without departing from the spirit of the invention so long as the broad results sought to be achieved are accomplished by means which operate in accordance with the principles described herein.

What I claim is:

1. In combination, with clock mechanism, including an arbor actuated thereby, power take-off devices and time indicating means carried with the arbor, and releasable means supported on and co-operating with said arbor to change the angular relation between the time indicating means and the power take-off devices with respect to the arbor without disturbing the angular relation between the power take-off devices and the time indicat-

ing means, and independent releasable means for setting the power take-off devices in pre-determined relation with the time indicating means.

2. In combination with clock mechanism an arbor actuated thereby and having a set screw secured in its end co-axially therewith, a removable sleeve mounted revolubly on the set screw and adapted to be secured thereby
10 in fixed relation to the arbor, power take-off devices and time indicating mechanism supported adjustably on the sleeve and a lock nut threaded on the sleeve and adapted to secure the power take-off devices and time indicating mechanism in desired position.
15

This specification signed this 21st day of December, A. D. 1922.
